CLAIM

The ornamental design for a food container, as shown and described.

DESCRIPTION

FIG. 1 is a top perspective view of a first embodiment of a food container.

FIG. 2 is a bottom perspective view thereof.

FIG. 3 is a top perspective view of a second embodiment of the design of FIGS. 1 and 2, but shown as transparent.

FIG. 4 is a bottom perspective view thereof.

FIG. 5 is a top perspective view of the food container of the design of FIG. 1, attached to a beverage container.

FIG. 6 is a bottom perspective view thereof, attached to a beverage container.

FIG. 7 is a top perspective view thereof, detached from a beverage container and a condiment container.

FIG. 8 is a bottom perspective view thereof, detached from a beverage container and a condiment container.

FIG. 9 is a top view of the design of FIG. 1.

FIG. 10 is a bottom view thereof.

FIG. 11 is a front view thereof, the rear view being a mirror image.

FIG. 12 is a right side view thereof; and,

FIG. 13 is a left side view thereof.

The broken lines showing a beverage container and condiment container illustrate environmental structure. All other broken lines illustrate portions of the food container. The broken lines form no part of the claimed design.
